J. SANDERS

QUICK RELEASE DEVICE FOR TANK CLOSURES

Filed Aug. 11. 1922

Fig. 1.

UNITED STATES PATENT OFFICE.

JOHN SANDERS, OF DENVER, COLORADO, ASSIGNOR TO SAFETY TANK DRAINAGE CO., A COMMON LAW TRUST, E. M. DAVIS, J. B. FORSHAY, JOHN SANDERS, C. E. WAMPLER, L. K. HANEY, AND CARLE WHITEHEAD, TRUSTEES, ALL OF DENVER, COLORADO.

QUICK-RELEASE DEVICE FOR TANK CLOSURES.

Application filed August 11, 1922. Serial No. 581,091.

To all whom it may concern:

Be it known that I, JOHN SANDERS, a citizen of the United States, residing at Denver, in the county of Denver and State of Colorado, have invented certain new and useful Improvements in Quick-Release Devices for Tank Closures; and I do hereby declare the following to be a full, clear, and exact description of the invention, such as will enable others skilled in the art to which it appertains to make and use the same.

This invention relates to a quick release device for tank closures, and more particularly to a device adapted for use in connection with tanks or similar reservoirs used for the storing of combustible fluids. The object of the present invention is to provide a device of the character indicated embodying a simplified structure adapted to application to tank closures already in use, and a further object is to provide a device of the character indicated of an inexpensive, simple, but at the same time, a positive and reliable character.

The invention consists in the novel construction, arrangement and combinations of parts hereinafter more particularly described and claimed.

One sheet of drawing accompanies this specification as part thereof, in which:—

Figure 1 is a plan view of the invention, parts being broken away to more fully illustrate its operation;

Fig. 2 is a fragmentary sectional view taken on line 2—2 of Fig. 1;

Fig. 3 is a front elevation of one of the clamping units;

Fig. 4 is a fragmentary detail sectional view taken on the line 4—4 of Fig. 5, and

Fig. 5 is a detail sectional view taken on the line 5—5 of Fig. 2.

Referring to the drawings, 1 indicates the wall of the tank structure to which is secured a port 2 having a flange 3 to which in turn is secured a face plate 4. A closure member 5 provided with a suitable annular gasket 5' adapted to engage with face plate 4 is provided and this closure plate 5 is provided with a plurality of spaced peripheral angular shoulders 6.

Secured to the face plate 4 at spaced intervals about its periphery, are supporting members comprising radially disposed bear-

ing arms 10 and 11. Each clamping member has two of the arms 10 which extend outwardly and are provided with aligned bearings 9 adapted to receive a pivot 9' upon which is supported a lever 8 provided on one end with a projection 7 adapted to engage a peripheral lug 6 of the closure plate 5. The arm 11 of each clamping member is formed on its outer end into a yoke 12, to the arms of which are pivotally connected pulleys 13. A lever 15 is pivotally supported upon arm 11 carrying on its inner end two angularly disposed pulleys 16—17 and upon its other end is provided a lug 18 adapted to slide in a slot 19 provided in the lever 8. Single pulleys 20 are suitably secured to port 2 one on either side of pulley 17, as is well illustrated in Fig. 1. Additional guide pulleys 20' may be placed around port 2 if desired, intermediate the respective pairs of the pulleys 20.

A cable C is provided with a loop c which loop is passed successively through pulleys 20—17—20 and over the guide pulleys 20' while a cable C' provided with a loop c' is passed around pulleys 13—16—13 of the successive clamping units.

In operation, it will be apparent that a pull upon cable C will operate through loop c to draw pulleys 17 inward toward pulleys 20, thus operating lever 15 and in turn through lug 19, lever 8 to draw the clamping member 7 out of engagement with the angular shoulder 6 of the face plate and thus release the closure 5. To close the device, a pull upon cable C' will operate through loop c' to draw pulleys 16 outwardly toward pulleys 13, reversing the motion of lever 15 and hence through lug 19 of lever 8 to swing the clamping member 7 into engagement with lug 6.

To permit adjustment of the device to varying face plates or to take up wear in the gaskets, lever 15 is adjustably mounted upon arm 11 by providing in the latter a slot extending perpendicular to the plane of the closure plate. The pivot 14 for lever 15 is provided with oppositely disposed parallel faces 14' adapted to slide in this slot and set screws 22 threaded through arm 11 from opposite sides permit the adjustment of the pivot 14' as may be desired. By varying the fulcrum point of lever 15 in the direction

indicated, it will be apparent that the operation of lever 8 can be modified to vary the degree through which the clamping member 7 will be operated.

5. Various modifications in the precise arrangement and construction of the parts will readily suggest themselves to those skilled in the art, but fall within the scope of the present invention.

10. Having thus fully described my invention, I claim:

1. The combination of a port, a closure, a plurality of clamping devices spaced circumferentially of the port, and means operative of said clamping devices whereby they may be entirely withdrawn beyond the circumference of the closure.

15. The combination of a port, a closure, a plurality of clamping devices mounted circumferentially of the port, and common means operative of said clamping devices whereby they may be entirely withdrawn beyond the circumference of the closure.

20. A clamping device for securing a closure to a port adapted to be mounted circumferentially of the port and comprising a pivoted clamping member, a lever having pulleys mounted on one end and its other end in operative engagement with the 25 clamping member, cords playing in said pulleys and guide pulleys for each cord oppositely disposed so that tension applied to

said cords in the same direction will operate said lever in opposite directions.

30. A clamping device for securing a closure to a port adapted to be mounted circumferentially of the port and comprising a pivoted clamping member, a lever having pulleys mounted on one end and its other end in operative engagement with the clamping member, an adjustable fulcrum for said lever, cords playing in said pulleys and guide pulleys for each cord oppositely disposed so that tension applied to said cords in the same direction will operate said lever in 35 opposite directions.

40. A quick release closure device comprising in combination a port, a closure adapted to be forced into sealing relation with the face of the port, a plurality of clamping levers pivotally mounted circumferentially on the port, levers one operative of each of said clamping members, said operative levers each having two pulleys on one end, cords looped and passed each successively 45 through one of the pulleys on each operative lever, and guide pulleys for each of said cord loops whereby tension on said loops in the same direction will operate said levers in opposite directions but all in unison in 50 either direction.

55. In testimony whereof I affix my signature.

JOHN SANDERS.
